(57) **CLAIM**

The ornamental design for a telecommunication device, as shown and described.

DESCRIPTION

FIG. 1 is a top, front, right perspective view of a telecommunication device according to our new design;

FIG. 2 is a front view thereof;

FIG. 3 is a right side elevational view thereof;

FIG. 4 is a left side elevational view thereof;

FIG. 5 is a top plan view thereof;

FIG. 6 is a rear end view thereof; and,

FIG. 7 is a bottom plan view thereof.

The broken line representations in the figures show unclaimed environment or boundaries, and thus form no part of the claimed design.

The nature of this product is a telecommunication device, such as a telephone or portion thereof.
